UNITED STATES PATENT OFFICE.

WILLIAM G. KENDALL, OF NEWARK, NEW JERSEY.

COMPACT HOLDER AND EJECTOR.

Application filed October 7, 1927. Serial No. 224,659.

This invention relates to compact holders and ejectors for vanity cases, and has for an object to provide an improved construction wherein an automatic ejector is presented, capable of functioning when manually released.

Another object of the invention is to provide an improved ejector mechanism for vanity cases, wherein an ejecting spring is utilized to produce a movement of the compact after the same has been released.

A further object of the invention, more specifically, is to provide a compact ejector, wherein one or more manually actuated catches are provided for holding a compact in place, together with a constantly acting spring positioned to eject the compact when the catches have been moved to a released position.

An additional object of the invention is to provide an improved compact holder wherein a releasable catch is presented for normally holding a compact against removal.

In the accompanying drawing—

Figure 1 is a top plan view of a vanity case open and provided with an embodiment of the invention, part of the lid being broken away.

Figure 2 is a view similar to Figure 1, except the compact has been removed and the lower part shown in section, said section being taken on line 2—2 of Figure 4.

Figure 3 is a sectional view through Figure 1 on line 3—3.

Figure 4 is a sectional view similar to Figure 3 except the compact has been removed.

Figure 5 is a plan view of a modified form of catch to that shown in Figure 1.

Figure 6 is an edge view of the catch shown in Figure 5.

Referring to the accompanying drawing by numerals, 1 indicates a lid of any desired structure hingedly connected at 2 to the body 3 of the vanity case. The body 3 may be of any desired shape, said body being formed preferably with a slightly curved bottom 4, though this is not at all essential. Bottom 4 merges at the sides into a curved flange 5 which accommodates the spring 6, which spring is in the form of a wire and part acting as a pintle for the hinge 2. The retaining spring 6 acts to clamp or hold in place, the compact holding ring 7. The ring 7 is provided with an annular flat surface

8 and a right angle flange 9 which is vertical when the surface 8 is horizontal. Flange 9 is preferably formed with a slight groove 10 in which the catch ring 11 fits. This catch ring is provided with a bent end 12 extending to an aperture in the flange 9, and extends almost entirely around the flange 9. At the end opposite the bent end 12, there is a vertical extension 13 projecting upwardly through a slot 14 in the surface 8. The extension 13 if desired, may be bent over and rounded to make a small smooth knob. Inwardly extending sections or ears 15 and 16 are formed at suitable spaced intervals by bending the ring 11. These extensions or catch members extend through suitable apertures in the flange 9 and overlap the annular flange or wall 17 of the compact 18. The compact 18 may be any desired compact, consisting usually of a flat bottom and an upstanding flange so as to present a cup structure for receiving the cosmetic.

As indicated particularly in Figures 2 and 3, the flange 9 merges into a bottom plate 19 which is provided with a slot or cut-away portion 20. A flat spring 21 is arranged beneath the plate 16 and is formed to normally bow upwardly as shown in Figure 4. The ends 22 and 23 of spring 21, continually remain in contact with the bottom 4, but whenever permitted, the spring will automatically move upwardly through the slot 20 into the position shown in Figure 4. When the compact is forced into the vanity case, it will snap past the catch members 15 and 16, and said catch members will normally hold the compact in place. As the compact is forced into position, spring 21 is forced downwardly until it assumes the position shown in Figure 3. When the projection or catch handle 13 is moved from the position shown in Figure 1 to the opposite end of the slot 14, catch ring 11 will be expanded and catch members 15 and 16 will be moved away from the compact. As soon as this has been done, the spring 21 will immediately function and will bow upwardly automatically to the position shown in Figure 4. This will result in raising the compact so that it may be readily grasped and removed and a new one substituted. In Figures 5 and 6, a modified form of catch ring 25 is disclosed. This ring is provided preferably with three catch members 26, though a greater or even less number

could be used. In this form of catch ring, there is provided a pair of upstanding projections or handles 27 and 28, each projection or handle being similar to the projection or handle 13. From Figure 5 it will be noted that these handles normally overlap so that in use, one will be on each end of the slot 14. To release the catch members 26, the thumb and one finger will engage these two handles and force them towards each other, whereupon the ring 25 will be expanded and the catch members 26 moved away from the compact.

What I claim is:

15 1. In a vanity case, a compact ejector comprising a catch structure for normally holding a compact in place, a constantly acting spring positioned to urge the compact to an ejected position, and manually actuated means for moving the catch structure to an inoperative position whereby said spring may function.

20 2. A compact ejector for vanity cases, comprising an ejecting spring, an expandible and contractable catch normally holding the compact in the vanity case against the action of said spring, and a hand operated member for moving said catch to an inoperative position.

30 3. A compact ejector for vanity cases, comprising a compact holding structure including a ring having a slot near one edge, a catch structure for holding a compact within said ring, a spring continually acting on said compact for ejecting the same, and a hand operated member extending from said catch structure through said slot whereby the compact structure may be moved to an inoperative position and thus permit the spring to function.

40 4. An ejector for vanity cases, comprising means for holding a compact in a case, said means including a ring formed with a bottom plate, said bottom plate having a slot therein, a spring carried by said case and positioned to move partly through said slot when released, a catch structure for normally holding the compact against said bottom plate whereby said spring is compressed, and a hand operated member for disengaging said catch structure whereby said spring may move partly through said slot for ejecting the compact.

50 5. An ejector for compacts, comprising a flat bowed spring adapted to be positioned beneath a compact when the compact is in an operative position, and a releasable catch for normally holding the compact in its operative position whereby when said catch is released said spring will automatically function to raise the compact to an ejected position.

60 6. In an ejector for vanity cases adapted to eject compacts therefrom, an ejector including a flat spring adapted to be posi-

tioned so that its ends will contact with the bottom of the case and the center will bow upwardly when released, means carried by the vanity case for receiving a compact, said compact acting to move said spring to a substantially flat position, and a releasable catch for normally holding the compact in the vanity case, said spring acting to eject the compact when the catch is released.

70 7. A compact plate holder and an ejector for vanity cases comprising a ring for receiving a compact plate, said ring being provided with a depending flange and a bottom plate formed with a slot therein, a catch for holding a compact plate in said ring, a spring functioning through said slot for ejecting said compact plate when said catch has been released, and a hand operated member for moving the catch to a released position.

85 8. An ejector for vanity cases, including means for holding a compact in a vanity case, said means being provided with a bottom having a slot therein, a flat loosely positioned spring arranged beneath said bottom and formed of a size to bow outwardly through said slot when released whereby the compact is ejected, and manually actuated catch means for normally holding the ejector against the action of said spring.

90 9. In an ejector for vanity cases, a ring structure having a depending flange formed with a plurality of apertures, a catch ring substantially surrounding said flange and formed with projecting catch members extending through said apertures, manually actuated means for causing said ring to expand and said catches to move to an inoperative position, and spring means positioned to act on the bottom of the compact 100 to move the compact out of the case when the catch members have been moved to an inoperative position.

100 10. In an ejector for compacts, a spring for ejecting the compact, and a catch structure for normally preventing the spring from functioning, said catch structure including a ring formed with a plurality of bent portions acting as catch members, and a pair of upstanding portions acting as 110 handles, said handles being adapted to be grasped and moved toward each other for causing the ring to be expanded when it is desired to move the catch members to a non-functioning position.

110 11. In a vanity case, a casing, a member mounted in said casing formed with a wall extending substantially at a right angle to the bottom of the casing, said member having an aperture, and a spring actuated catch extending normally through said aperture for releasably retaining a compact in said member.

120 12. In a vanity case, a casing, a compact receiving member mounted in said casing 125

formed with an upstanding wall provided with an aperture, a catch, a spring for normally holding said catch so that it will project through said aperture for retaining a compact in said member, and manually operated means for withdrawing said catch so as to release the compact held thereby.

13. In a vanity case, a compact holding member formed with an apertured wall, a plurality of catch members extending beyond said wall for holding a compact in said holding member, one of said catch members being withdrawable for releasing said compact, and spring means for normally holding said last mentioned catch member in engagement with said compact.
14. In a vanity case, a compact holding ring formed with an aperture, a spring pressed catch normally projecting through said aperture for retaining a compact in said ring, and manually actuated means for withdrawing said catch through said aperture for releasing said compact.

Signed at New York in the county of New York and State of New York this 5th day of October, A. D. 1927.

WILLIAM G. KENDALL.
